[57] CLAIM

The ornamental design for a door activated light switch, as shown and described.

DESCRIPTION

FIG. 1 is a left side elevational view of the door activated light switch of the present invention;

FIG. 2 is a right side elevational view of the door activated light switch of FIG. 1;

FIG. 3 is a front elevational view of the door activated light switch of FIG. 1;

FIG. 4 is a back elevational view of the door activated light switch of FIG. 1;

FIG. 5 is a top plan view of the door activated light switch of FIG. 1; and,

FIG. 6 is a bottom plan view of the door activated light switch of FIG. 1.

The broken lines shown in FIG. 1 are for illustrative purposes only and form no part of the claimed invention.
